CLAIM

The ornamental design for a bottle pressurizer with hose, as shown and described.

DESCRIPTION

FIG. 1 is a top, front, and left side perspective view of a bottle pressurizer with hose showing my new design; FIG. 2 is a top, front, and right side perspective view thereof; FIG. 3 is a top, rear, and left side perspective view thereof; FIG. 4 is a top, rear, and right side perspective view thereof; FIG. 5 is a bottom, front, and left side perspective view thereof;

FIG. 6 is a bottom, front, and right side perspective view thereof;

FIG. 7 is a left side elevation view thereof;

FIG. 8 is a right side elevation view thereof;

FIG. 9 is a front elevation view thereof;

FIG. 10 is a rear elevation view thereof;

FIG. 11 is a top plan view thereof; and,

FIG. 12 is a bottom plan view thereof.

The dash-dash broken lines represent portions of the bottle pressurizer with hose that form no part of the claimed

(Continued)

design. The short dash-long dash broken lines define boundaries of the claimed design and form no part of the claimed design.
